Primary Examiner — T. Chase Nelson*Assistant Examiner* — Mark Cavanna(74) Attorney, Agent, or Firm — Muncey, Geissler, Olds & Lowe, P.C.CLAIM

The ornamental design for a set of bottom bars for drawable basket, as shown and described.

DESCRIPTION

FIG. 1 shows a perspective view of a set of bottom bars for drawable basket showing my new design.

FIG. 2 shows a front view of the present design.

FIG. 3 shows a rear view of the present design.

FIG. 4 shows a left side view of the present design.

FIG. 5 shows a right side view of the present design.

FIG. 6 shows a top view of the present design; and,

FIG. 7 shows a bottom view of the present design.

The broken lines showing of structural feature is indeed for the purpose of illustrating non-claimed subject matter and forms no part of the claimed design.
